ATTY

UNITED STATES PATENT OFFICE.

HENRY J. GAISMAN, OF NEW YORK, N. Y.

DESIGN FOR A BELT-BODY.

SPECIFICATION forming part of Design No. 32,910, dated July 3, 1900.

Application filed April 9, 1900. Serial No. 12,252. Term of patent 3½ years.

To all whom it may concern:

Be it known that I, HENRY J. GAISMAN, a citizen of the United States, residing in New York city, borough of Manhattan, State of New York, have invented and produced a new and original Design for a Belt-Body, of which the following is a specification, reference being had to the accompanying drawings, forming part hereof, wherein—

Figure 1 is a face view of a body portion of a belt embodying my design, and Fig. 2 is a transverse section of the same on the line 2 2

As shown in the drawings, the leading or material feature of my design consists of a surface ornamentation comprising lines or ribs which converge longitudinally in opposite directions from the central portion of the belt-body, the opposed lines or ribs extending together at said central portion, and said ribs have spirally-disposed lines or depressions, producing a rope-like effect. The sur-

face ornamentation shown in the drawings comprises lines or ribs A, extending in converging lines in opposite directions from the central portion of the body B, the opposed lines or ribs A at the central portion of the body being curved inwardly and meeting at c, and the surface of the lines or ribs A have spirally-disposed lines or depressions a, producing a rope-like effect. In the central portion of body B is a conventional figure D, having spirally-disposed lines or depressions d, producing a rope-like effect.

Having described my invention, what I claim as new, and desire to secure by Letters Patent, is—

The design for a belt-body, as herein shown and described.

HENRY J. GAISMAN.
